UNITED STATES PATENT OFFICE.

J WALTER MOORE, OF FORT EDWARD, NEW YORK.

CHILD'S COMBINED CARRIAGE AND SLEIGH.

1,013,206

Specification of Letters Patent.

Patented Jan. 2, 1912.

Application filed March 9, 1911. Serial No. 613,456.

To all whom it may concern:

Be it known that I, J WALTER MOORE, a citizen of the United States, residing at Fort Edward, in the county of Washington 5 and State of New York, have invented certain new and useful Improvements in Children's Combined Carriages and Sleighs, of which the following is a specification.

This invention relates to improvements 10 in a combined child's carriage and sleigh, and has for one of its objects to simplify and improve the construction and increase the efficiency and utility of devices of this character.

Another object of the invention is to provide a device of this character which may be readily and quickly transformed from a 15 sleigh to a carriage, or from a carriage to a sleigh without detaching or removing any 20 of the parts, and which may also be employed as a brake to support the carriage from movement when required.

With these and other objects in view the invention consists in certain novel features 25 of construction as hereinafter shown and described and then specifically pointed out in the claims, and in the drawings illustrative of the preferred embodiment of the invention, Figure 1 is a side elevation of the 30 improved device with the runner attachment in elevated or inoperative position; Fig. 2 is a detached perspective view of one of the side bar members of the frame; Fig. 3 is a side elevation of the rear portion of 35 the improved device with the runner portion in lowered or operative position; Fig. 4 is a section on a line 4-4 of Fig. 3; and Fig. 5 is an enlarged sectional detail on the 40 line 5-5 of Fig. 1. Fig. 6 is a perspective view of the forward supporting rod together with its bracket arm detached.

Corresponding and like parts are referred 45 to in the following description and indicated in all the views of the accompanying drawings by the same reference characters.

The improved device may be applied without material structural changes to the framework of children's carriages of various makes, but for the purpose of illustration 50 is shown applied to the base framework of a child's conventional carriage, the framework being represented conventionally at 10 and embraces spaced side members and transverse end members, as shown, and with 5 an upwardly curved portion to which the handles are attached, as represented at 11.

The improved device is designed more particularly for use upon the class of child's carriages called "go-carts," and the framework 10-11 of this class of vehicles is 60 represented.

The improved attachment comprises two main runners coupled for vertical movement to the framework 10 and carrying the bearing wheels of the vehicle, and the construction and manner of operating this portion 65 of the device is the principal feature of the present invention.

The side structures of the improved device are precisely alike, except that they are 70 made lefts and rights, and the description of one will suffice for both.

The main portion of the attachment comprises a longitudinal supporting member 12 having vertical end portions 13-14, the portion 13 having bearing collars 15 at its ends, while the portion 14 is provided with similar bearing collars 16 at its ends. The bearing 75 collars are represented at 17 and are mounted upon stub axles 18 which are connected to the side members 12 adjacent to the vertical portions 13-14. The runners of the improved device embrace horizontal central portions 19 and upwardly and inwardly curving end portions 20-21. Each of the 80 runners including the curved end portions is formed from a single piece and preferably with the central portion 19 semicircular, while the ends 20-21 are tubular, the 85 tubular portions merging into the central 90 semicircular portion, as shown. At its upper end the curved portion 20 is enlarged into a head 22, while the terminal of the curved portion 21 terminates in a similar 95 head 23. The head 22 is formed with an aperture to receive a vertical rod 24, while the head 23 is apertured to receive a similar 100 rod 25. At its lower end the rod 24 is forked, as shown at 26, and fitting within the forked portion is a block 27 which is 105 riveted or otherwise secured respectively to the forked portion 26 and the semicircular portion 19 of the runner, and the lower end of the rod 25 is correspondingly forked and riveted to a block, similar to the block 27, the block being likewise riveted to the 110 adjacent portion of the runner. By this means the rods 24-25 are firmly united to the runner portion and extend vertically therefrom. At its upper end the rod 24 is turned over above the head 22 and extended 115 downwardly through the aperture in the

head and extended rearwardly in the form of a bracket 30, while the upper end of the rod 25 is likewise turned over and passed downwardly in the apertures in the head 23, as shown at 31. The side rails 10 of the vehicle frame extend beneath the turned-over portions of the vertical guide members 24-25 and are held thereby from upward movement, while the heads 22-23 bear beneath the frame rails and thus serve as clips to firmly couple the side rails, runners and guide members. Pivoted at 32 to the bracket 30 is an elbow lever 33, while a similar elbow lever 34 is pivoted at 35 to the downwardly directed portion 31 of the rod 25. The lever 34 is provided with a rearwardly extending treadle member 36, as shown. One of the arms of each of the elbow levers 33-34 is coupled by a rod 37, 20 while the other arm of each elbow lever is coupled respectively by chains 38-39 to the bearings 15-16 of the members 13-14. Surrounding the rod 24 between the bearing 15 and the runner 19-20-21 is a 25 spring 40, while a similar spring 41 surrounds the rod 25 between the lower bearing 16 and the runner. The springs are connected at their ends respectively to the runners and the bearings and thus exert 30 their force to maintain the runners yieldably in their upward position.

Depending from the head 23 of the curved terminal 21 of the runner is a stop 42 with which the chain carrying arm of the 35 elbow lever 34 engages when the rod 37 is pulled a little below the center, to limit the movement of the lever and its attachments and thus form a locking device to maintain the runners in their lowered position and 40 the springs distended and the wheels out of contact with the ground. When the parts are in this position the improved device is in condition to be employed as a sleigh, and when it is desired to transform the sleigh 45 into a carriage it is only necessary for the attendant to draw the treadle 36 rearwardly to break the "lock" of the rod 37, when the reaction of the springs 40-41 will immediately and automatically elevate the runners 50 into the position shown in Fig. 1, with the wheels bearing upon the ground.

The improved device will also be found of great advantage for employment as a brake to hold the upper frame from movement 55 when desired. Thus if the attendant desires to leave the carriage with its occupant for a time, she simply depresses the treadle 36 until the chain bearing arm of the lever 34 engages the stop 42, when the carriage 60 portion will be elevated and the runners caused to engage the ground, and thus act as an effectual brake and prevent the movement of the carriage.

The improved device is simple in construction, can be inexpensively manufac-

tured and applied without material structural changes to carriage frames of various forms by slight and immaterial changes in the construction of the portion 10 of the carriage.

Having thus described the invention, what is claimed as new is:-

1. In a combined child's carriage and sleigh, runners, each of said runners having vertical guide members near the ends, side 75 bars in slidable engagement with said vertical guide members, ground wheels carried by said side bars, springs operating to maintain said runners yieldably in their elevated position relative to said side bars, 80 means for elevating said side bars and the ground wheels carried thereby against the force of the springs, and locking means operating to hold said runners in their lowered position. 85

2. In a combined child's carriage and sleigh, a vehicle frame including side rails, runners having vertical guide members, each guide member having a bracket arm spaced therefrom, means for coupling said guide members to said side rails, side bars in slidable engagement with said vertical guide members, ground wheels carried by said side bars, springs operating to maintain said runners yieldably in their elevated position relative to said side bars, a lever carried by each of said bracket arms and operating to elevate said side bars against the resistance of said spring, coupling means between said levers and said side bars, coupling means between 90 said levers, and a locking device connected to one of said levers. 95

3. In a combined child's carriage and sleigh, runners, each of said runners comprising a body portion and rearwardly curving end portions, a vertical guide member extending between each of the terminals of the runners and the body portion thereof and spaced apart, side bars having bearings at the ends for slidable engagement with the guide members, springs connected to said runners and to said side bar bearings, an operating lever connected to each of said guide members, coupling means between said operating levers and said side bars, and a coupling device between said operating levers. 110

4. In a combined child's carriage and sleigh, runners having vertical guide members, side bars slidably engaging the guide members, a bracket arm extending from each of said guide members, an elbow lever pivoted upon each of said brackets, coupling means between one arm of each of said elbow levers and the side bars, a connecting rod between the other arms of the elbow levers, and a lever arm connected to one of said elbow levers. 125

5. In a combined child's carriage and sleigh, runners having vertical guide mem-

bers, side bars slidably engaging the guide members, a bracket arm extending from each of said guide members, an elbow lever pivoted upon each of said brackets, coupling means between one arm of each of said elbow levers and the side bars, a connecting rod between the other arms of the elbow levers, a stop in the path of one of said elbow levers and located beyond the vertical plane of the adjacent guide member, whereby when the elbow levers are moved into one position one of the pivots of the connecting rod will be disposed below the line of the elbow lever to which it is attached and held by the stop from further downward movement and the runners locked from return movement.

6. In a combined child's carriage and sleigh, runners each comprising a body portion and inwardly curving end portions, a vertical guide member connected at its lower end to the body portion near each end of the same and with a downwardly directed bracket arm extending from the upper end, a vehicle frame including side rails and extending between the bracket arms and the guide members, clips connected to the inwardly curving ends of the runners and

bearing around the guide members and the bracket arms below the frame rails, side bars slidably engaging the guide members, an elbow lever pivoted upon each of said bracket arms, coupling means between one arm of each of said elbow levers and the side bars, and a connecting rod between the other arms of the elbow levers.

7. In a combined child's carriage and sleigh, runners each comprising a body portion and inwardly curving end portions, a vertical guide member connected at its lower end to the body portion near each end of the same and curving inwardly and downwardly at the upper end, a vehicle frame including side rails and extending beneath the curving terminals of the guide members, and clips connected to the inwardly curving ends of the runners and bearing around the guide members and the curved upper terminals of the same, whereby the runners and frame rails are connected.

In testimony whereof, I affix my signature in presence of two witnesses.
